EVERETT S. CAMERON, OF TOTTENVILLE, NEW YORK

VALVE ACTION FOR INTERNAL-COMBUSTION ENGINES

Application filed March 17, 1928. Serial No. 262,456.

The present invention relates to improvements in valve-actions for internal combustion engines. The invention has reference more particularly to a construction of the 5 type wherein each engine cylinder is provided with two inlet valves and two outlet valves, each pair of inlet valves being actuated by a rocker-shaft and each pair of exhaust valves being acted upon by another 10 rocker-shaft.

The main objects of the invention are to provide a construction of this type wherein provision is made for properly guiding the actuating means for each pair of valves; to 15 produce a design of this type which is exceedingly simple in construction, efficient in operation, durable in use, and wherein proper lubrication of the moving elements is obtained.

Another object of the invention is to so 20 design the actuating means that the strokes of the valves may be conveniently varied, according to the requirements.

With these and other objects in view, 25 which will more fully appear as the nature of the invention is better understood, the same consists in the combination, arrangement and construction of parts hereinafter described, pointed out in the appended claim 30 and illustrated in the accompanying drawings, it being understood that many changes may be made in the size and proportion of the several parts and details of construction within the scope of the appended claim, 35 without departing from the spirit or sacrificing any of the advantages of the invention.

One of the many possible embodiments of 40 the invention is illustrated in the accompanying drawings, in which:—

Figure 1 is a front elevation of a valve actuating means constructed in accordance with the present invention; Fig. 2 is a section taken on line 2—2 of Fig. 1; Fig. 3 is 45 a section taken on line 3—3 of Fig. 1; Fig. 4 is a front elevation of the rocker-lever operated sleeve of the device; and Fig. 5 is a side elevation of the element shown in Fig. 4.

In the drawings, the numeral 10 indicates

a portion of one of the valve cages of an engine cylinder, said cage being provided with valve seats 11, with which co-operate two inlet valves 12 of the poppet type. Each valve is provided with a stem 13 which extends through a guide 14, the latter being made in the form of a separate piece and held upon the valve cage in a manner hereinafter to be described. The stem is provided adjacent its outer end with a reduced 55 portion 15, into which is fitted a stop 16 of any suitable construction. Against this stop bears a spring seat 17, and in alignment therewith is held against a shoulder 18 on the guide 14 a valve seat 19. Between these 60 two seats is arranged a spring 20, coiled around the valve stem and serving to hold the valve in its closed position, as shown in Figs. 2 and 3 of the drawings. The valve stem is provided at its outer end with a reduced 65 portion 21, whereby a shoulder 22 is formed thereon. On this reduced portion is mounted a contact screw 23, bearing against the shoulder 22 and being carried by an 70 arm hereinafter to be described.

The valve actuating means comprises a 75 rocker-shaft 24, mounted in a stationary bearing sleeve 25. This rocker-shaft co-operates with a pair of inlet valves, as shown in Fig. 1 of the drawings, it having fixed to 80 its upper end, above the bearing sleeve 25, a rocker-lever 26 in engagement with an anti-friction roller 27, the latter being mounted upon a sleeve 28. This sleeve is slidably 85 mounted, in the direction of its longitudinal axis, upon a hollow spindle or support 29. The spindle is fixed to the engine cylinder between a pair of inlet valves, in any suitable manner. The inner end of this spindle is in the case illustrated in the drawings 90 permanently closed by a screw bolt 30, which serves to fix the same to the engine cylinder. The outer end of the hollow spindle, on the other hand, is closed by a detachable screw plug 31. Into the said hollow spindle is 95 packed grease or a like lubricating material, which finds its way to the inner face of the sleeve 28 through openings 32. These openings extend radially through the hollow spindle. On the sleeve 28 are formed two 100

valve-operating prongs 33, each of which is provided with a screw-threaded bore 34, the threads of each bore meshing with those of a contact screw 23 above referred to. These contact screws bear, as above described, against the shoulders 22 of the valve stems 13.

The rocker-shaft 24 serves to reciprocate the sleeve 28 on the spindle 29. When the sleeve is moved in the direction of the arrow shown in Fig. 2 of the drawings, the pair of inlet valves are moved toward opening positions, the springs 20 returning the same to closing positions when the sleeve is moved in the opposite direction.

The sleeve and the valve-operating prongs 33 thereon are properly guided in their reciprocating movement by the said spindle. Friction between the sleeve and the spindle is reduced to a minimum by reason of the fact that the grease that is packed into the hollow spindle finds its way to the interior surface of the sleeve through the openings 32 above described. The contact screws 23 permit of regulating the proper amount of opening to be given the valves.

It is obvious that, while herein the construction and operation of the actuating means for the inlet valves of an engine cylinder have been described, the invention is applicable to exhaust valves without any change in the design of said actuating means. It is also obvious that, while herein a specific valve construction has been described, the actuating means herein disclosed are adapted to be used in connection with other valves just as well, the invention lying mainly in the provision of a pair of valve-operating prongs which are reciprocably mounted upon a support and guided by the latter in their alternating movement, in combination with means for properly lubricating the contact surfaces between the valve-operating prong carrier and its supporting guide.

What I claim is:

The combination with a valve cage provided with two valve seats, of two spring-controlled valves co-operating with said seats, said valves being normally maintained in their closed positions by the springs co-operating therewith, a stationary hollow guide spindle arranged in parallel relation to the stems of said valves, said spindle being adapted to contain lubricating material, a sleeve reciprocably mounted on said spindle, said spindle being provided with openings leading from its interior to that face of said sleeve which contacts with said spindle, whereby the lubricating material finds its way to the inner face of said sleeve, two prongs on to said sleeve in engagement with said valves, an anti-friction roller on said sleeve, and a rocker-shaft provided with a lever in engagement with said anti-friction roller for longitudinally shifting said sleeve, whereby said valves are simultaneously

moved toward open positions in relation to their valve seats against the action of their springs when said rocker-shaft is actuated.

Signed at New York, in the county of New York, and State of New York, this 25th day of February, A. D. 1928.

EVERETT S. CAMERON.
